UNITED STATES PATENT OFFICE

WILLIAM KUSHLIN AND HERMAN KESNER, OF BROOKLYN, AND IRVING OLTSIK, OF NEW YORK, N. Y.

DESIGN FOR A PILLOW

Application filed February 21, 1930, Serial No. 34,624. Term of patent 3½ years.

To all whom it may concern:

Be it known that we, WILLIAM KUSHLIN, HERMAN KESNER, and IRVING OLTSIK, a citizen of the United States, a citizen of the Republic of Hungary, and a citizen of the United States, respectively, and residents of Brooklyn, in the county of Kings and State of New York, of Brooklyn, in the county of Kings and State of New York, and New York, in the county of Bronx and State of New York, respectively, have invented a new, original, and ornamental Design for Pillow, of which the following is a specification, reference being had to the accompanying drawing, forming part hereof.

We claim:

The ornamental design for a pillow, as shown.

WILLIAM KUSHLIN.
HERMAN KESNER.
IRVING OLTSIK.
